AIR-COOLED TANK FOR ELECTRICAL APPARATUS.

1,155,656.

Specification of Letters Patent.

Patented Oct. 5, 1915.

Application filed December 23, 1913. Serial No. 808,477.

To all whom it may concern:

Be it known that I, ISAAC HARTER, a citizen of the United States, residing at New York city, borough of Richmond, county of Richmond, and State of New York, have invented certain new and useful Improvements in Air-Cooled Tanks for Electrical Apparatus, of which the following is a specification.

My invention relates to air-cooled tanks containing a fluid where it is desired to dissipate heat supplied to the fluid by electrical apparatus contained in said tank, and to maintain the temperature of the fluid within certain working limits, and has been designed more particularly for use as a tank for cooling transformer coils. Such tanks are ordinarily made either with plain or corrugated surfaces, the amount of surface being made large enough to produce sufficient cooling, or they are made with tubes inserted in the walls of the tank in such a manner as to permit temperature differences in the different levels of the fluid to set up a circulation through the tubes and through the tank. The cooling effect of a tank of given outside dimensions can be made greater in a tank provided with cooling tubes than in a plain or corrugated tank, due to the facility with which the tube surface can be added to the tank, also because the fluid is divided into smaller bodies, and again because convection currents of air rising among the tubes can more thoroughly reach the surface.

One of the disadvantages of a tank constructed in the ordinary manner with circular cooling tubes is that radiation from the walls of the tank itself is largely prevented by the tubes unless the number of such tubes is kept small. Another disadvantage is that if the diameter of the tubes is increased to increase the surface, the rate at which heat can be taken from the fluid which circulates through the tubes is decreased, so that in practice the tubes must necessarily be small in diameter and spaced closely together, which leads to complication and increase in cost.

My invention relates to tanks provided with cooling tubes and consists in a particular form and arrangement of such tubes, and will be understood by reference to the accompanying drawings in which—

Figure 1 is a top view with some of the tubes in section; Fig. 2 a side elevation,

partly in section; Fig. 3 a longitudinal section, the tank being placed horizontal; and Fig. 4 a horizontal section on the plane of the line 4—4 of Fig. 2.

Similar reference numerals indicate similar parts in the several views.

Referring to the drawings the numeral 1 designates a tank of suitable dimensions and form for the apparatus for which it is to be used, such as a transformer casing. 65 Tubes 2 are inserted into the walls of the tank, said tubes being flattened in planes normal to the tank. The tubes are preferably vertical and extend from the lower to the upper end of the tank and are fitted into 70 openings 3 of the same section as the ends of the tubes. The construction shown in the drawings is the one preferred by me but it is obvious that the advantages incident to the flattened tube would still obtain, in a 75 modified degree, if the tubes were flattened in part, or if they entered the tank at various angles and at various points. In transformers oil is the cooling medium, and to make tight joints the tubes may be welded 80 to the tank. The oil enters the upper parts of the tubes and on being cooled increases in density and flows downward through the tubes on account of the gravity head.

An advantage in the use of flattened tubes 85 is that large tubes may be flattened to give the same thickness of the cross-section of the fluid as exists with smaller circular tubes, with the result that the rate at which heat is communicated from the fluid to the walls 90 of the tubes will not be decreased, as it would be should the large tubes be used without flattening them. A further advantage is that for a given spacing of the flattened tubes more surface of the tank is 95 exposed for radiation than where round tubes are employed, and there is more freedom for circulation of air currents than exists with round tubes. A greater number of the flattened tubes can also be effectively 100 attached to the tank with the tube holes entering at the same level than with round tubes.

In transformers it is highly essential that 105 the heat produced by the electric current be conveyed away as rapidly as formed, otherwise the temperature of the apparatus would increase and would finally reach a dangerous point. Again, the temperature of the apparatus should be maintained as little above that 110

of the surrounding air as possible, as the efficiency may be decreased through an increase in temperature. In a tank such as described I dispose the surface so as to obtain a maximum cooling effect through combined radiation and conduction to the surrounding air, and thereby provide an apparatus which is particularly adaptable to the work it accomplishes.

10 By using tubes flattened or having their greatest axis on lines substantially normal or radial to the tank, the radiation from the tank walls for a given perimeter of a tank is greater than with round tubes. Furthermore, with two tanks of the same diameter and the same amount of external tube cooling surface, the flattened arrangement gives a greater area between the tubes for the flow of convection air currents than with round tubes. For the same reason, there is a greater entrance and exit area for the upwardly flowing convection air currents at the junctures of the tubes with the tank. Again, there is a special advantage in using flattened tubes containing oil and exposed to the air for the reason that oil is relatively a poor conductor of heat and by flattening the pipe the film of oil is thinner and the speed at the different points in the cross section is more nearly the same than in a circular pipe, thus aiding in heat transfer.

What I claim and desire to secure by Letters Patent of the United States is:—

35 1. An air-cooled tank arranged to contain a fluid to dissipate heat from an electrical apparatus, said tank having connected to its walls a plurality of tubes exposed to the air and through which the fluid circulates, the cross-sections of said tubes having axes of different lengths and the longest axes lying in planes substantially normal to the tank.

40 2. An air-cooled tank to contain a fluid

to dissipate heat from an electrical¹ apparatus, said tank having inserted in its walls a plurality of tubes through which the fluid circulates, said tubes having at least a portion whose cross section is flattened where they are acted on by the air, and disposed in planes substantially normal to the surface of said tank.

3. An air-cooled tank to contain a fluid to dissipate heat from an electrical apparatus, said tank having inserted in its walls a plurality of tubes through which the fluid circulates, said tubes having at least a portion whose cross section is flattened where they are acted on by the air, and disposed about the tank in a substantially vertical position.

4. An air-cooled tank arranged to contain a fluid to dissipate heat from an electrical apparatus, said tank having connected to its walls a plurality of substantially vertical tubes exposed to the air and through which the fluid circulates, the cross-sections of said tubes having axes of different lengths and the longest axes lying in planes substantially normal to the tank.

5. A tank designed to dissipate heat from electrical apparatus, said tank having a plurality of flattened tubes projecting outwardly from its wall.

6. A tank designed to dissipate heat from electrical apparatus, said tank having a plurality of tubes projecting outwardly therefrom and having at least a portion whose cross section is flattened.

In testimony whereof I have hereunto signed my name in the presence of two subscribing witnesses.

ISAAC HARTER.
